UNITED STATES PATENT OFFICE.

THOMAS N. FURLONG, OF SAN FRANCISCO, CALIFORNIA.

COMBINED WASHTUB AND SINK.

No. 909,392.

Specification of Letters Patent.

Patented Jan. 12, 1909.

Application filed August 5, 1908. Serial No. 447,107.

To all whom it may concern:

Be it known that I, THOMAS N. FURLONG, a citizen of the United States, residing at San Francisco, in the county of San Francisco and State of California, have invented certain new and useful Improvements in a Combined Washtub and Sink; and I do hereby declare the following to be a full, clear, and exact description of the invention, such as will enable others skilled in the art to which it appertains to make and use the same.

This invention relates to combined wash-tubs and sinks, and more particularly to a structure of the character referred to especially adapted for use as an inside fixture for kitchens where economy of space is a desideratum, particularly in apartment houses or flats.

The invention will first be hereinafter more particularly described with reference to the accompanying drawings, which are to be taken as a part of this specification, and then pointed out in the claims at the end of the description.

In said drawings, Figure 1 represents a vertical longitudinal sectional elevation of a combined washtub and sink embodying my invention; portions of the tub and sink being broken away to avoid the necessity for illustrating the full length of either. Fig. 2 is a detail view partly in section of a chamber at the bottom of the washtub showing its connection with the waste-pipe. Fig. 3 is a detail view partly in section of a portion of the overflow pipe and circular chamber at its top.

Referring to said drawings, in which the same reference letters are used to denote corresponding parts in different views, the letter A may denote a washtub preferably formed of reinforced cement molded in one piece with an ordinary porcelain enameled sink B embedded in the cement during the process of molding, as will be understood by those skilled in the art to which the invention relates.

The letter C denotes a suitable chamber, which may be of cast metal, also embedded in the cement bottom of the tub, and having an open top provided with a top plate or cover c having a suitable aperture therein to receive a thimble D through which the liquid contents of the tub may flow into said

chamber. The cover c is preferably provided with marginal ribs or flanges c' which overlap the sides or upper edges of the chamber C, and the latter has a lateral tubular extension C' which is interiorly screw-threaded to receive a short exteriorly threaded sleeve E. The cover c may terminate short of said tubular threaded portion or extension C' of the nipple to provide an intervening space to receive the lower end of an overflow pipe or tube F embedded in the cement wall dividing the tub and sink, said tube being preferably elliptical or oval shaped in cross-section and made of zinc to prevent corrosion. A circular or other suitable chamber f may be soldered or otherwise secured upon the upper end of said overflow pipe and provided with a perforated disk or guard plate F'. As shown, the overflow pipe and the inlet chamber thereon are embedded in the cement molding forming the solid wall between the washtub and sink but a different arrangement might be employed without departing from the spirit and scope of my invention.

The letter G denotes a discharge pipe, preferably nickel-plated brass tubing, threaded at one end and screwed into an elbow section g secured to the sink-outlet, the other end of said discharge pipe having a slip-joint connection with the discharge chamber C, so that it may be slid a greater or less distance therein for the purpose of making the desired connection between the chamber C and the sink-outlet. Over the discharge pipe G is fitted an interiorly threaded nut or collar H, preferably of nickel-plated brass, which is screwed upon the sleeve E, and within which is placed a rubber or other suitable washer or gasket I, and, preferably, a brass ring j, to protect the rubber washer or gasket from grinding away while tightening up the joint. At its upper end the elbow section of the discharge pipe G is provided with a flared end g' conforming in shape to the downwardly flaring protuberance or nipple K on the bottom of the sink, and between these flaring portions may be placed a ring of putty k, such as ordinarily employed in connecting sinks to waste-pipes.

The chamber C is preferably formed with a circular bottom having an angular pipe-like terminal for connection with the waste-pipe

L, which is preferably of lead and has its upper end flared and fitted over or upon said pipe-like end or bottom of the chamber C, and also having a correspondingly shaped 5 ring M thereon adapting it to be screwed up tightly against the angular terminal of the chamber C so that the end of the lead pipe will be spread out to form a secure connection and water-seal between the two parts, 10 which may be secured together by means of bolts N passed through apertured lugs n and m on the chamber C and ring M, respectively, as shown.

On account of the unequal expansion and 15 contraction of cement and metal, the cement around the porcelain-lined sink is liable to crack as it hardens or "sets," and to avoid this difficulty, and at the same time to adapt the sink to be easily removed when damaged 20 and to permit another sink to be substituted in its stead, without injuring or damaging other parts of the structure, I may place between the cement body and the outer sink a layer or layers of soft material, such as felt, 25 between layers of water-proof material, preferably tar-paper, as at O, thus forming a cushion on which the sink is seated and which will yield sufficiently during the shrinking process to prevent the cement from 30 cracking, and being firmly embedded in the cement the sink may be easily removed and replaced without affecting the cushion or other parts of the structure. The water-proof material prevents the moisture in the 35 cement, which always seeks the surface, from evaporating too quickly and thus conduces to the formation of a more compact body of cement without crack or blemish resulting from the shrinkage.

40 I thus provide a very simple and efficient strong and durable combined wash-tray and sink, without lead-pipe wiped joints and which will occupy but a small space and may be manufactured at a comparatively small 45 cost.

It will be understood, of course, that various changes may be made in the form and arrangement of the parts, and in the material used, without departing from the principle 50 and scope of my invention, and hence I do not desire to be restricted to the specific construction and arrangement of parts shown or described.

Having thus described my invention, what 55 I claim as new and desire to secure by Letters Patent of the United States is:

1. A combined washtub and sink composed of a body of suitable cement with a porcelain enameled sink embedded in the cement 60 at one side of the tub and a metallic chamber embedded in the cement of the tub bottom, said chamber having a pipe-connection with the sink-outlet and with a waste-pipe, and an opening in its top to provide an

outlet for the tub, so that both tub and sink 65 discharge through said chamber into the same waste-pipe.

2. A combined washtub and sink composed of a body of reinforced cement molded in one piece with a porcelain enameled sink 70 embedded in the cement at one side of the tub, and a metallic chamber embedded in the cement forming the tub bottom; said chamber having openings in its top and bottom through which the liquid contents of the 75 tub may be emptied, and pipe-connections between said chamber and the sink outlet and between its bottom opening and a waste-pipe.

3. A combined washtub and sink 80 composed of a body of suitable cement with a porcelain enameled sink embedded in the cement at one side of the tub and a metallic chamber embedded in the cement of the tub bottom, said chamber having an opening in 85 its top to provide an outlet for the tub and a tubular extension at one side, pipe-connections between the sink-outlet and said extension having a slip-joint connection with the latter, and means for connecting said 90 chamber with a waste-pipe.

4. In combination with a tub and sink forming a compact concrete structure with a metallic sink at one side of the tub and a metallic chamber at the bottom of the tub 95 forming a part of said structure, means for connecting said chamber with a waste-pipe and an adjustable pipe-connection between said chamber and the sink-outlet.

5. In combination with a tub and sink 100 forming a compact concrete structure of cement with a metallic sink at one side of the tub and a metallic chamber at the bottom of the tub forming a part of said structure, means for connecting said chamber with a 105 waste-pipe and an adjustable pipe-connection between said chamber and the sink-outlet, together with an over-flow-pipe embedded in the cement wall uniting the tub and sink and leading into said chamber. 110

6. A combined washtub and sink composed of a body of suitable cement having a porcelain enameled sink embedded therein at one side of the tub, an over-flow pipe embedded in the division wall between the tub 115 and sink, and a metallic chamber embedded in the tub bottom, said chamber having suitable openings in its top to receive said over-flow pipe and provide an outlet for the tub, and having a pipe-connection with the sink-outlet together with means for connecting said chamber with a waste-pipe. 120

7. A combined wash-tub and sink composed of a body of reinforced cement molded to form a tub and a sink at one side thereof, 125 the latter having a metallic vessel and an interposed cushion of soft material embedded in the cement.

8. A combined wash-tub and sink composed of a body of cement molded in the desired form, a metallic sink embedded in the cement at one side of the tub and a layer of
5 felt between two layers of water-proof material interposed between the cement and sink.

In testimony whereof I affix my signature, in presence of two witnesses.

THOMAS N. FURLONG.
